UNITED STATES PATENT OFFICE.

YOSHITO IWATA, OF BUFFALO, NEW YORK.

COMBINED CHAIR, TABLE, AND FIRE-ESCAPE.

1,265,203.

Specification of Letters Patent.

Patented May 7, 1918.

Application filed March 23, 1916. Serial No. 86,224.

To all whom it may concern:

Be it known that I, YOSHITO IWATA, a citizen of Japan, residing at Buffalo, in the county of Erie and State of New York, have invented certain new and useful Improvements in Combined Chairs, Tables, and Fire-Escapes, of which the following is a specification, reference being had therein to the accompanying drawing.

10 This invention relates to improvements in fire escapes and has for its primary object the provision of a fire escape which may at all times be conveniently located for use in case of emergency, while at the same time adapted to perform other functions in the field of useful household furniture.

20 The invention more particularly comprehends a fire escape employed in a combination designed as a chair, table or desk dependent upon the relation of the adjustable or interchangeable parts as will more fully hereinafter appear.

25 The invention further embraces a fire escape made up of a plurality of foldable members adapted to be closed into parallel relation and in pairs, the pivots being arranged at alternate ends, in combination with a combined guide and grip adapted to 30 slide downwardly over said members when extended; more specifically, the guide and grip being provided with spaced devices adapted to alternately interfit with complementary and like portions of the members 35 when the combined grip and guide sleeves over the alternating outside and inside bars.

The invention still further comprises many improved details in construction and arrangement of parts, all as will be brought 40 out in the specific description hereinafter contained when read in connection with the accompanying drawings forming part hereof and wherein the preferred embodiment of the invention is illustrated.

45 In the drawings:

Figure 1 is a perspective view of the complete device;

Fig. 2 is a vertical sectional view through the sides of the device;

50 Fig. 3 is a similar view through the front and back of the device;

Fig. 4 is a sectional view showing the fire escape in use;

Fig. 5 is a perspective view showing the manner of folding the foldable seat of the 55 fire escape;

Fig. 6 is a detail transverse section through one of the foldable bars of the fire escape showing the co-operation of the combined grip and clamp with a pair (inside and outside) of said bars;

Fig. 7 is a rear view of the device;

Fig. 8 are respectively plan and longitudinal sectional views of the chair arms showing the manner of elongating or contracting the same;

Fig. 9 is a fragmentary sectional view showing the application of a desk or table top to the fire escape body, with the chair arms and back removed; and

Fig. 10 is a perspective view of a shelf unit adapted to be detachably placed on the table top as indicated in the preceding figure.

Referring more specifically to the drawings, wherein like reference characters designate corresponding parts throughout the several views. A represents a flat base having a pair of parallel cleats B on the surface for detachably centering the same 80 within the substantially rectangular frame C having the up-rights D at the corners thereof, the side members of the frame being composed of overlying sections c provided with a series of apertures c' into 85 which, when registered, locking pins c² may be removably inserted to bring the front and rear uprights to greater or less distances apart for the purpose to be later brought out. Passing through the upper 90 ends of the forward pair of up-rights D is a rod E having shoulder portions e adjoining reduced ends to which detachable nuts e' are threaded to bind against the outer faces of the up-rights D.

Loosely sleeved upon the rod E between the shoulders e thereof and the inner faces of the up-rights D, one at each side of the device, is the first bar F of a great number of similar bars connected and arranged, 100 when unfolded, to constitute an elongated fire escape ladder adapted to depend from a window or other opening in a building. These bars are arranged in pairs which I will designate the inside and outside bars, 105 F' denoting the inside and F² denoting the

outside bars. The first inside bars F' at their rear ends and the corresponding rear end portions of the immediately adjoining outer bars F^2 are pivoted on rods E' similar to the rods E , and adapted to constitute the ladder rungs, said alternating pivoted arrangement being carried on throughout the extent of said bars to enable the nesting thereof as clearly illustrated to constitute a chair body, or the unfolding thereof and elongation to constitute the before mentioned fire escape ladder as will be readily understood.

Near the ends of the bars F' , they each carry tapered guide lugs or securely fastened projections G operating to automatically align the bars when they are undergoing the folding action, and serving as spacing members to separate the ladder from the wall when the ladder hangs without the building to perform its function as a ladder, this spacing of the ladder from the wall, as is obvious, being intended to accommodate the hands and feet of the user, and to afford space for the travel of a combined clamp and grip which will presently be described.

It will be observed that the first lowermost inside bar F is the only one secured to the up-rights D , this adjustment being shown at the front, the first outside bars resting on the tops of the up-rights at said front and the rear ends of the same bars resting upon the tops of the rear up-rights but held against upward movement therefrom by a tie member H having a hook h at one end adapted to engage over the pivot bar or rung of the uppermost inside bars F' and having a rounded catch h' at its lower end to be sprung over a cross rod h^2 bridging the upper ends of the rear up-rights D , the resiliency of the bars, all of them being formed of metal, being such as to permit the engagement of the tie member and by spring action hold the tie member when in place.

Similarly formed tie members I engage the uppermost and lowermost tapered rods or rungs both at front and rear of the fire escape portion when folded or nested; and an additional tie member J sprung over one of the front rungs and engaging a cross rod j of front arm supports h to tie said arm support to the folded ladder body, the rear arm supports being pivoted on the terminal portions of the uppermost rear pivot rod or rung of the ladder, all of these rungs save the pivot rod E first mentioned being designated E' .

60 The rear legs h continue upward to constitute a chair back h' connected to the front legs h at a suitable distance above the top of the ladder body by arms K , the same being formed of sections adapted to slide upon each other through the medium of wire loops or brack-

ets k^2 and to be locked in adjusted positions with the front and back legs separated at desired distances apart by means of double headed keys k^3 adapted to be introduced through elongated slots k^4 , so that the keys 70 when enlargements k^5 of the slots are in registration, may be turned at an angle to their position of introduction so as to cross the slots and enter the enlargements, thus locking the members of the arm against displacement. L is a chair bottom which may be plain or suitably upholstered or provided with a separate cushion in keeping with custom, the characteristic of the bottom residing mainly in its formation proportioned to 80 fit between the opposite upper inside bars of the ladder body and with the ends l of the front and rear frame members of the bottom projecting over some of the lugs or projecting parts G of the inside ladder bars 85 to thus support the bottom, and behind others of said lugs or projections to prevent play of the bottom from front to rear of the ladder body.

Each of the bars of the ladder body is 90 grooved centrally throughout the length of its upper and lower surfaces to constitute when the ladder is unfolded or extended what may be styled a broken, staggered, or irregular guide way extending along the 95 front, and also one extending along the rear of the ladder.

100 M are the combined grip and guiding members the same being of U-shape having the arms m and connecting portion m' the arms being adapted to ride along the front and rear faces of the bars F' and F^2 when extended with the connecting portion m' disposed laterally at the sides and recessed as at m^2 to pass over the nuts on the threaded 105 ends of the pivot bars or rungs E' . These members M carry two pairs of oppositely disposed guide pins m^3 m^4 projecting inwardly into the space between the arms m , the former pins being adapted to interlock 110 with the front and rear grooves of the inside ladder bars and the latter to interlock with the corresponding front and rear grooves in the outer ladder bars when extended, thus effecting a continuous guiding 115 function from the top to the bottom of the ladder as the member alternately passes over the inner and outer bars F' and F^2 . To that form of the U-shape members M now under consideration which is presented forwardly 120 when the ladder sections are extended I provide grips m^5 which may be utilized by a person in sliding down the ladder when any suitable rope or belt may be engaged with the body if need be, the weight applied 125 to the grips causing the tilting or canting action of the U-shape members so that the arms M will frictionally engage the front and rear faces of the ladder bars and prevent a too rapid descent.

Preferably, I suspend from the combined guides and grips a platform or seat N conveniently formed of wire, and of an improved foldable character including horizontal end rods n telescopically related vertical supporting rods n^1-n^2 , and jointed diagonal supporting rods n^3-n^4 pivotally connected as at n^5 to the outer ends of the horizontal rods n and pivotally and slidably connected at their upper ends to the vertical rods n^2 , the lower ends of the vertical rods n' being similarly pivotally connected to the inner ends of the horizontal rods n. The telescopic function, and the pivoting function is accomplished in each instance by looping the rod members around each other as illustrated, it being observed that the loops at the upper end of the jointed diagonal supporting rods overlie the loops at the ends of the upper members of the vertical supporting rods to limit the outward movement of the seat or platform N. The seat terminates about midway of the horizontal supporting rods n so that ample space is provided between the inner edge of said seat and the wall or ladder for the accommodation of the legs of the occupant, this rendering it easy for the occupant to utilize his legs in forcing the seat or platform away from any possible catching or binding engagement with the remainder of the structure when the same is traveling downwardly, and also enables the occupant to face the building to prevent dizziness, and to facilitate the engagement of the grips m^5 and proper manipulation thereof to secure the release of the frictional holding action of the members M on the ladder bars.

The folding of the platform or seat just described will be clear from the drawings but it may be here observed, when not in use, when the same is to be placed at the back of the chair, it is simply necessary to fold inwardly the diagonal supporting rods and then slide the same together with the lower vertically supporting rods n' upwardly along the upper vertical supporting rods n^2 , the outer bar of the seat or platform engaging over the hooks N' pivoted upon the uppermost pivot rod or rung at the back of the chair.

There are casters carried by the lowermost ladder bars when folded to constitute the body of the chair and may be utilized to directly support said body and the remainder of the structure thereabove upon the floor by simply removing the frame C with its uprights D from the foldable ladder portion incident to the withdrawal of the pivot rod E passing through the lowermost ladder bars and the upper ends of the uprights D', and removing the tie member H holding the ladder body to the cross bar bridging the rear uprights.

As shown in Fig. 9, the chair back and

arms may be removed by springing off the appropriate front tie member and removing the rear cross bar bridging the rear arm supports k and pivotally engaging the uppermost ladder bars. When this is done the base member A may be inverted and laid upon the ladder body to serve as a table or desk top, the cleats M thereof fitting between the upper side bars of the ladder body and the top being held in place by engaging appropriate tie members J^2, J^3 therewith as shown, the tie members springing over rods P bridging the ends of the cleats B.

It is here observed that when the arms and back are in position the combined grip and clamping members M are disposed on the rear arm supports, suitable grooves Q being formed in the front and rear faces thereof for the reception of the outer series of guide pins, it being remembered that the supports k are in the plane with the outer ladder arms, and thus the combined grips and guides are in position to be slid downwardly over the ladder bars when the fire escape is in use, all that is necessary to permit such use being to pull off the tie members, when the chair arms and their supports may be fitted over a bottom portion of a window frame and adjacent wall to anchor the fire escape to said window, the ladder simply dropping downwardly along the wall from the pivoted connection with the rear members k of the arm support. The means enabling the elongation or shortening of the chair arms afford ready facility for fitting the same to varying widths of window frames and walls as will be obvious.

When the device is in use as a table the combined grips and guides may then occupy a position upon the forward uprights D, the latter being grooved along its front and rear faces as indicated at R for this purpose. Here, the frame C with said upright will constitute the means for spanning the window sill and associated parts to hold the ladder as the same is permitted to open in falling downwardly from the pivoting cross rod E bridging the forward uprights D. In this instance also it is simply necessary to pull off the spring held tie members to release the ladder from the rear uprights D, and the ladder sections from each other, as well as to release the double top when the top may be instantly thrown aside and out of the way.

The various grooves through which the pins of the combined grips and guides work are flared at their upper and lower ends to facilitate the entrance of the pins therewith when passing from one ladder bar to the succeeding ladder bar.

T is a shelf or ledge attachment fashioned to fit and be detachably connected to the top A as at t when the device is to constitute a desk top as will be readily under-

stood, this attachment being removed or stored when the desk is not desired or when the top A constitutes the base support as first hereinabove suggested.

5. To strengthen the U-shape combined grips and guides M bolts and nuts W may be passed through the terminal portions of the arms thereof as illustrated.

10 While I have herein shown and described a special embodiment of my invention, it will be understood by persons skilled in the art to which the invention appertains, that said invention is capable of embodiment in other forms and devices involving various 15 alterations and changes in detail and relative arrangement of parts, all as may be in keeping with the hereto appended claims.

I claim:—

1. In a fire escape, the combination of pivoted sections provided with side bars adapted to be folded into approximately parallel relation when not in use, certain of the side bars being provided with projections to center the bars in their folding operation 25 and a detachable seat having portions adapted to fit between the folded side bars when nested and be supported by the adjacent projections.

2. In a fire escape the combination of pivoted sections provided with side bars adapted to be folded into approximately parallel relation when not in use, certain of the side bars being provided with projections to center the bars in their folding operation and a 35 detachable seat having portions adapted to fit between the folded side bars when nested and be supported by the adjacent projections and be retained against endwise movement by others of said projections.

40 3. In a fire escape the combination of side bars pivot rods connecting the same to enable the bars to fold into an approximately parallel position when not in use, and means for retaining the same in folded position 45 comprising detachable tie rods engaging the pivot rods, said pivot and tie rods being yieldably related to retain the tie rods in position by spring action.

4. In a fire escape the combination of side 50 bars pivot rods connecting the same to enable the bars to fold into an approximately parallel position when not in use, and means for retaining the same in folded position comprising detachable tie rods engaging the pivot rods, the tie members having hooks at 55 one end and rounded catching portions at the other end.

5. A fire escape comprising pivotally related sections having side bars, said side 60 bars being grooved lengthwise thereof, and a combined gripping and guiding member adapted to traverse the side bars when extended, said member being arranged to engage opposite faces of the side bars to grip

the same when canted and having a projection adapted to engage the way formed by the grooved portions of the side bars. 65

6. A fire escape comprising a plurality of pivotally related sections adapted to be extended when in use and to be folded into substantially parallel relation when not in use with some of the bars occupying an inside and others an outside relation, said bars being grooved longitudinally thereof, and a combined grip and guide adapted to engage 75 opposite faces of the bars to grip the same when canted, said combined grip and guide having a pair of projections adapted to ride in the ways constituted by the groove portions of the bars as the combined grip and 80 guide members traverse alternately over the inside and outside bars.

7. A fire escape comprising a plurality of pivotally related sections adapted to be extended when in use and to be folded into substantially parallel relation when not in use with some of the bars occupying an inside and others an outside relation, said bars being grooved longitudinally thereof in their opposite faces, and a combined grip and 90 guide member adapted to engage said opposite faces of the bars to grip the same when canted, said combined grip and guide members having an aligned pairs of projections adapted to ride in the ways constituted by 95 the grooved portions of the bars as the combined grip and guide members traverse alternately over the inside and outside bars.

8. A fire escape comprising pivotally related sections having side bars, said side bars being grooved lengthwise along their opposite faces, and a combined grip and guide member adapted to traverse the side bars when extended, said member being arranged to engage said opposite faces of the guide 100 bars to grip the same when canted and having projections adapted to engage the ways formed by the grooved portions of the side bars.

9. In a fire escape, side bars adapted to 105 extend along the face of a building, guiding means adapted to traverse said bars, and a foldable seat associated with said guiding means, said seat comprising horizontal and vertical members and diagonal foldable 115 members extending from the vertical members to the outer portion of the seat, the horizontal and vertical members being pivoted together, and the diagonal foldable members each consisting of sections pivotally connected to each other, the foldable diagonal members at their upper ends being pivotally and slidably connected to the vertical members. 120

10. In a fire escape, side bars adapted to 125 extend along the face of a building, guiding means adapted to traverse said bars, and a seat associated with said guiding means, said

seat comprising horizontal and vertical members and diagonal foldable members extending from the vertical member to the outer portion of the seat, the horizontal and vertical members being pivoted together and said vertical members being formed of telescopic sections slidably related to the upper ends of the diagonal foldable members.

11. In a fire escape, a plurality of foldably related sections adapted to be extended when in use and to be folded into approximately parallel position when not in use, one of said sections carrying a securing means, and a foldable seat mounted to traverse the sections when extended, and having a part to be engaged by said securing means to retain the seat in folded position when not in use.

12. In a convertible device of the character described, a hollow supporting frame member, a base upon which the hollow frame member is adapted to rest, having cleats adapted to fit within the hollow frame member but removable therefrom, an extensible fire escape foldably related to said hollow frame member and adapted to rest thereupon when not in use and comprising spaced side bars adapted to receive therebetween said cleats of the base to enable said base to be used as a top.

13. In a device of the character, a body portion having side members and cross bars providing a space therebetween at the top, and a top member adapted to rest on the side members, said top having cross bars on its under surface, and tie members adapted to engage the cross bars of the top and body member to detachably secure them together.

14. In a fire escape, an under frame having upright members, an extensible portion adapted to extend along the wall of a building when in use and to be supported in folded relation upon the under frame when not in use, one end of said extensible portion being pivotally connected to one edge of the frame so that when the foldable section is extended and supported on said pivotal connection, the upright portions of the frame may engage around a window sill or the like.

15. In a fire escape, an under frame having upright members, an extensible portion adapted to extend along the wall of a building when in use and to be supported in folded relation upon the under frame when not in use, one end of said extensible portion being pivotally connected to one edge of the frame so that when the foldable section is extended and supported on said pivotal con-

nection the upright portions of the frame may engage around a window sill or the like, the frame being extensible to adjust the uprights to greater or less distances apart.

16. In a fire escape, a foldable body portion adapted to be extended to occupy a position along the wall of a building when in use and to present a seat support when in folded position, in combination with a back and arms having front and rear supporting portions, said front and rear supporting portions extending downwardly from the arms in substantially parallel relation and resting upon the said foldable body portion when the same is in folded position, the foldable body portion being pivotally connected to one of said supporting portions so that when the foldable body portion is extended the said front and rear supporting portions may engage around a window sill or the like.

17. In a fire escape, a foldable body portion adapted to be extended to occupy a position along the wall of a building when in use and to present a seat support when in folded position, in combination with a back and arms having front and rear supporting portions, said front and rear supporting portions extending downwardly from the arms in substantially parallel relation with each other and resting upon the foldable body portion when the same is in folded position, the foldable body portion being pivotally connected to a pair of the arm supporting portions so that when the foldable body portion is extended the said front and rear arm supporting portions may engage around a window sill or the like, the arms being extensible, and means for securing the same in adjusted positions, substantially as described.

18. In a fire escape, a frame having a portion adapted to occupy an upright position, an extensible section adapted to occupy a folded relation to the frame when not in use, a movable connection between the end of said extensible section and said upright portion, and a guide member formed to travel over the extensible section when unfolded, said member being constructed to normally occupy a position on said upright portion and to pass along the same to the extensible section, substantially as described.

In testimony whereof I hereunto affix my signature in the presence of two witnesses.

YOSHITO IWATA.
